UNITED STATES PATENT OFFICE.

EDWARD A. OWENS, OF SAN FRANCISCO, CALIFORNIA, ASSIGNOR TO SELECTASINE SYSTEM INC., OF SAN FRANCISCO, CALIFORNIA, A CORPORATION OF CALIFORNIA.

STENCIL PRINTING MACHINE.

Application filed July 6, 1921. Serial No. 482,678.

To all whom it may concern:

Be it known that I, EDWARD A. OWENS, a citizen of the United States, residing at the city and county of San Francisco and State of California, have invented new and useful Improvements in Stencil Printing Machines, of which the following is a specification.

This invention relates to a printing machine and especially to a multi-color printing machine in which the colors are selected, applied to the surface of a stencil, and transferred therethrough one by one.

Heretofore in Patent No. 1,254,764, entitled Method of delineating or reproducing pictures and designs, issued Jan. 29, 1918, and in my co-pending applications April 16, 1919, Serial No. 290,374, and April 14, 1920, Serial No. 373,828, I have described a method of printing and reproducing multi-color pictures, designs, etc., which consists in tracing or otherwise outlining a picture on a fabric screen or similar partially penetrable material; masking certain areas as outlined to form a stencil on the screen, and applying and transferring the colors one by one through the unmasked areas.

In actual operation when employing the method outlined, hand operation has been entirely resorted to, that is the paint or other color employed is poured on the screen or stencil and then spread and transferred by a hand-operated squeegee. Hand operation is strenuous work. It requires that a man use heavy pressure on the squeegee to force the thick paint through the screen and as this operation is ordinarily repeated several thousand times during a day's work, it can readily be imagined that the work is, comparatively speaking, exhausting. General observation has shown that the quality of the work decreases as the operator tires, that is uniformity of product is not obtained, the output decreases and the paint employed is either wasted or disadvantageously employed.

One of the objects of the present invention is to generally improve and simplify the operation of applying and transferring the paint or other material employed; to greatly increase the output; to materially increase the uniformity and quality of the work; to economize, first, by reducing the quantity of paint or other coloring matter used; second, to reduce the number of spoils; third to

lessen the wear and tear of the screen or stencil, and finally to lessen the labor and skill otherwise required.

Another object of the invention, and one more specifically stated, is to provide a machine, comprising a table for the reception of the stock or material to be printed; a stencil supporting frame, means for automatically raising and lowering the frame, and means for automatically applying and transferring colors through the stencil.

Another object of the invention is to provide means whereby a predetermined register may be easily and quickly obtained between the stencil and the stock to be printed; and further to provide means cooperating therewith for automatically ejecting the stock when printed.

Another object of the invention is to provide means whereby the screen supporting frame may be longitudinally and laterally adjusted with relation to the table and the lifting frame.

Further objects will hereinafter appear.

The invention consists of the parts and the construction, combination and arrangement of parts as hereinafter more fully described and claimed, having reference to the accompanying drawings, in which—

Fig. 1 is a side elevation of the machine.

Fig. 2 is a front end view of the same.

Fig. 3 is a plan view of the machine.

Fig. 4 is an enlarged longitudinal cross section of the lifting frame, the stencil supporting frame carried thereby and the squeegee.

Fig. 5 is a transverse cross section of the lifting frame and the stencil supporting the frame carried thereby, said view also showing the squeegee and its supporting frame in end view.

Referring to the drawings in detail, A indicates a main frame of suitable construction upon which is supported a table 2. Disposed within the frame and journaled crosswise thereof, is a main cam shaft 3, a secondary cam shaft 4, a rocker shaft 5, and a second rocker shaft 6. Journalled lengthwise of the frame is a main drive shaft 7 and an auxiliary rocker shaft 8. The main drive shaft may be connected with an electric motor or any other suitable driving mechanism not here shown. Secured on the drive shaft is a worm pinion 9, and intermeshing therewith is a worm gear 10, which

is keyed or otherwise secured on the main cam shaft 3. Continuous rotary movement is in this manner transmitted to the main cam shaft and a similar movement is transmitted to the secondary cam shaft 4 by means of a beveled gear drive indicated at 11 and 12. Disposed on top of the table is a lifting frame 14. Supported therein is a stencil frame 15, and also supported thereby is a pair of longitudinally extending channel shaped track members 16, between which is disposed a squeegee supporting frame generally indicated at 17. The main frame 14 is intermittently raised and lowered with relation to the table to permit insertion and automatic ejection of the stock to be printed. The entire frame is lifted by means of a tilting movement; this being accomplished by securing the rear end of the frame to a cross shaft 18, which is journaled at the rear end of the table 2. Secured on the cross shaft is a crank arm 19, and adapted to impart an intermittent rocking movement thereto, at predetermined time intervals, is a link 20, and a rocker arm 21 pivotally secured on the main frame A, as at 23. Adapted to impart an intermittent rocking movement to the arm 21, is a cam 24. This cam is secured on the main shaft 3 and it has a shape such as generally indicated by dotted lines at 24 in Fig. 1. A roller on the lower end of the rocker arm 21 engages one side of the cam. This side of the cam imparts a rocking movement to raise or tilt the frame 14 with relation to the shaft 18 and as the frame drops by gravity when released by the cam, it is obvious that the other side of the cam merely controls or retards the lowering speed of the frame. A second cam 25 secured on the shaft 3 engages a roller 26 secured at the outer end of a crank arm 27. This arm is secured on the rocker shaft 6, which shaft also carries a pair of rocker arms 28, disposed one on each side of the frame. (See Figs. 1, 2 and 3.) The upper ends of the arms are slotted as at 29 and a cross head 30 is slidably mounted in the slotted portion of each arm and so connected with the squeegee frame 17 that a reciprocal movement is transmitted thereto between the channel shaped guide tracks 16 when engagement is made between the cam 25 and the crank arm carrying the roller 26. The positioning of the cams 24 and 25 is such that a complete reciprocal movement will be imparted to the squeegee frame when the main frame 14 is lowered or supported by the table. The squeegee frame is otherwise disposed near the rear end of the frame 14 and remains stationary at this point when the frame 14 is being raised and lowered by means of the cam 24. In fact the position of the cam 25 as shown in Fig. 1, is such that the squeegee frame has just reached its extreme forward position and

is ready to be retracted or returned to its normal stationary position at the rear end of the frame 14. One-half a revolution of shaft 3 is required to impart a reciprocal movement to the squeegee frame through the medium of the arms 28, while during the other one-half revolution of the shaft, the squeegee and arms 28 remain stationary. It is during this rest period that the cam 24 engages the rocker arm 21 and that the tilting movement is imparted to the lifting frame 14, such tilting movement being permitted as the slight vertical movement imparted to the rear end of the lifting frame is taken care of by the slots 29 and the cross heads slidably mounted therein. 70

The main cam shaft serves three functions, first that of raising and lowering the lifting frame 14; secondly that of imparting one reciprocal movement to the squeegee frame, one during each revolution; and third, that of transmitting power to the secondary cam shaft 4 through means of the beveled gears indicated at 11 and 12. The secondary cam shaft, as previously stated, is continuously rotated in unison with the main cam shaft 3. It carries three sets of cams indicated at 31, 32 and 33. The cam 33 actuates the mechanism whereby the printed stock is automatically ejected after each printing operation. It will therefore be referred to as the ejecting cam. This cam is nothing more or less than a collar such as shown in Fig. 2, which is secured to the shaft 4. One face of the collar is provided with an angular beveled edge 34 in which is formed a recess 35. One side of the recess is parallel with the longitudinal axis of the shaft 4 as shown at 36, while the other side of the recess is gradually inclined and forms a part of the angular face 34. Engaging the working face of the cam is a crank arm 37 which is secured on a shaft 38 longitudinally disposed with relation to the main frame A and journaled therein. Secured on the shaft are two knock-out fingers 39 and connected with the crank arm 37 is an ejecting spring 40. During the rotation of shaft 4 and the ejector cam 33 secured thereto, it is obvious that the end of the crank arm 38 will normally engage the angular face 34 formed on the cam and as the direction of rotation is that indicated by arrow a, see Fig. 2, it is obvious that the drop in the cam ends indicated at 35 will be reached and that the crank arm will suddenly be released and thus instantly retracted by the spring 40. The shaft 38 is thus rocked and the knock-out fingers 39 carried thereby will engage one side of the stock and strike the same with such force that the stock is ejected. This of course takes place the moment the stock has been printed and the lifting frame 14 raised. Continued movement of the cam 33 will cause the inclined 85

face 36 to engage the crank arm and the shaft 38 will again be rocked and the fingers retracted in readiness for the next knock-out or ejecting operation.

8 The cam indicated at 31 is employed for the purpose of transmitting a rocking movement to the rocker shaft 5. This is accomplished by hanging a link 41 on the shaft 4, that is the link is slotted as at 42 and hangs 10 on the shaft 4. The lower end of the link is connected through a crank arm 43 with the rocker shaft 5, while the upper end is provided with a roller 44, which rides on the cam 31. This cam has a raised portion 15 which, when engaging the roller 44, transmits a reciprocal movement to the link 41 with relation to the shaft 4. This reciprocal movement is of course transmitted to the crank arm 43 and a rocking movement is 20 thus finally transmitted to the shaft 5. This shaft performs two functions, first that of transmitting a vertical reciprocal movement by a rod 47^b to one of the registering fingers projecting through the table and indicated 25 at 45; and secondly that of transmitting a rocking movement to the rocker shaft 8; the transmission of movement from shaft 5 to 8 being accomplished by connecting the shafts by means of a pair of beveled gears 30 46, see Fig. 2. The shaft 4 also imparts a reciprocal movement to a link 47; the link 47 being operated by means of a cam 32 on the shaft 4.

35 Before proceeding further with the general description of the mechanism employed, it might be well to state that six registering fingers are employed for the purpose of positioning and securing the stock during the printing operation. One of the registering fingers is indicated at 45, and the remaining fingers at 49, 50, 51, 52 and 53. The fingers 49 and 50 are operated by one part 40 of the mechanism hereinafter to be described; the finger 45 by the mechanism already described, and the fingers 51, 52 and 53 by another part of the mechanism to be hereinafter described. The finger 45 has a vertical movement to project or lower it 45 with relation to the table surface and it also has a jogging and a gripping movement. The fingers 49 and 50 may be termed gripping and jogging fingers as they have both a vertical movement and a jogging movement, and the fingers 51, 52 and 53 may be 50 termed gripping fingers as they only have a vertical movement. The mechanism operating the fingers 49 and 50 is partially actuated by the rocker shaft 8. This rocker shaft has two crank arms secured thereon 55 which straddle vertically disposed rods 54; one of the fingers, 49, being secured on one rod and the other finger 50 on the other rod. A rocking movement imparted to the shaft 8 is transmitted through the crank arms 60 to raise the rods 54 and the fingers 49 and

50 carried thereby, and springs disposed at the lower ends of the rods indicated at 55, serve the function of lowering or retracting the same. The cam 32 secured on shaft 4 will, through the medium of link 47, and a 70 sliding rod 48, transmit a rocking movement to a bell crank indicated at 56, (see Fig. 3) and through a link 57 connected therewith a jogging or tilting movement is transmitted to the rods 54 and the fingers 49 and 50 as 75 the opposite end of the link 57 is attached to a plate connecting the rods 54, as indicated at 80 58. In other words vertical movement is imparted to the fingers 49 and 50 by the shaft 8, and a jogging movement is transmitted from shaft 4 through the mechanism generally indicated at 33, 47, 48, 56, 57 and 85 58. The rod 48 has a collar 47^a secured thereon and this serves the function of engaging the finger 45 and simultaneously imparting a jogging movement thereto. The upper ends of the fingers 49, 50, 51, 52, 53 and 45, are hook shaped as shown at 59. They are therefore adapted to grip the edge 90 of the card or stock to be printed and thereby secure it against vertical movement with the lifting frame when this is raised as will hereinafter be described. The fingers 51, 52 and 53 are secured to a triangular shaped plate disposed below the table and indicated 95 at 60. This plate is secured on the upper end of a rod 61, and this rod is actuated by means of a cam 62 secured on the link 20, that is a roller is secured on the rod 61 and this roller is engaged by the cam 62. A 100 vertical raising movement is thus transmitted to the rod 61, the plate 60 and the fingers 51, 52 and 53 carried thereby, and a lowering or clamping movement with relation to the table is transmitted by means of 105 a spring 63 interposed between the lower end of the rod and the main frame A, see Fig. 1.

110 The entire driving mechanism and the parts actuated thereby have now been described and a detail description of the squeegee frame, the lifting frame and the screen or stencil frame carried thereby will now follow:

115 The main lifting frame has previously been indicated at 14. It is rectangular in shape and is preferably constructed of angle iron as shown at 64, see Figs. 4 and 5. The screen supporting frame is preferably made of wood and is generally indicated at 120 65. It is also rectangular in shape and the lower face of the sides and the ends of the frame 65 are channeled to receive clamping strips 66. The screen employed is generally constructed of finely woven silk. The 125 silk indicated at 67 is secured with relation to the frame 65 by means of the clamping strips 66 and is in this manner tightly stretched and securely supported; the clamping strips being secured in any suitable

4

manner, or as here shown by means of screws 68. One of the end sections of the frame 65, or that indicated at 69, in Fig. 4, is adjustable to permit the screen or silk fabric 67 to be tightened lengthwise; the adjustment being obtained by means of a threaded ferrule 70 and a screw 71. Again it is possible to obtain adjustment of the main frame 65 and the registering fingers on the table by means of combined adjusting and clamping screws indicated at 72. These screws secure the frame 65 within the lifting frame and they permit both lateral and longitudinal adjustment as specified. The channel shaped tracks running longitudinally of the lifting frame, and disposed one on each side thereof, are secured in any suitable manner. They serve the function of supporting the squeegee frame and guiding the same during its reciprocal movement with relation to the stencil. This is accomplished in the following manner:

The squeegee consists of a pair of head members, see Figs. 4 and 5, generally indicated at 73. Journalled on each head member is a pair of spaced rollers 74 which enter the channelled shaped tracks 16, thereby forming guides and supports for the heads 73. The heads 73 are connected by means of a pair of cross bars 75, said cross bars being secured to the heads by means of screw 76. The cross bars are interspaced as shown in Fig. 4, and disposed between the same is a pair of interspaced guide and supporting plates 77 and 78, between which is interposed a squeegee 79. Also interposed between the plates 77 and 78 is a top plate or bar 80, and engaging the same are a suitable number of adjusting screws 81, whereby vertical adjustment of the squeegee may be obtained; the screws 81 being carried by cross clips such as shown at 82. Vertical adjustment of the squeegee between the plates 77 and 78 is obtained by means of the screws 81 and the bar 80, and clamping of the squeegee to retain such adjustment is obtained by two or more clamping screws 83 carried by the cross bars 75. These screws engage the plates 77 and 78, thereby forcing them together and clamping the squeegee 79 between the same. Also supported by the cross bars 75 is a paint receptacle 84. This receptacle consists of a piece of sheet iron or the like bent to form a pair of end sections 85 and a rear section 86. There is no top or bottom for the receptacle. The squeegee forms the front of the receptacle, the rear section 86, the rear side thereof, and the sections 85 the enclosures thereof. The paint deposited therein is however retained, first by the squeegee 79, secondly by a follower 87, and third by a pair of end squeegees or liners shown at 88. The squeegee in reality consists of a paint reservoir or container, a distributing blade 87, and a squeegee blade 79. These several elements operate in unison and form an exceedingly important feature of the present invention. During the forward stroke, paint leaves the reservoir in a thin film, which is regulated by the distributing blade 87. The distributing action causes the paint to fill the pores of the screen to a uniform surface. The squeegee on the return stroke removes any excess that may have been deposited on the screen and simultaneously presses or forces the remaining paint through the meshes or pores of the screen surface; this being accomplished with an even stroke and pressure that causes a uniform transfer and cleans the silk entirely of paint. The rounded edge of the squeegee 9 gives flexibility and decreases resistance when moving in one direction and causes removal of paint and the application of pressure during the return stroke. The supporting plates 77 and 78, together with the bar 80, permit the rubber squeegee to be adjusted to a fine degree, thus permitting the blade to engage the screen or silk uniformly throughout its length and at all points.

Another important feature is the provision of means for laterally and longitudinally adjusting the screen or stencil supporting frame with relation to the lifting frame. This is readily and quickly accomplished in the present instance by the adjusting screws indicated at 72 and is of importance as it permits absolute registry of the screen frame with relation to the card or stock secured between the registering fingers, for instance when changing colors or runs, etc.

Another important feature is the adjustability of the end sections 69, that is any sag or stretch imparted to the silk fabric naturally takes place in the direction of movement of the squeegee, most of which slack may be readily taken up as the ferrule 70 and the adjusting screw 71 are provided. The grippers or registering fingers, previously referred to, and particularly the hook portions formed thereon, are necessary to grip the card on the table surface particularly during the time period when the lifting frame is being raised. Paint is a sticky viscous body and has a tendency to adhere and lift the cards. This action will materially slow up the machine as a whole if permitted, and might in some instances even smudge the stock. However this is entirely obviated and taken care of by the grippers or registering fingers shown. The jogging movement imparted to the fingers 45, 49 and 50 is also of importance as it causes automatic registering and perfect registry, that is the operator merely inserts the card to be printed so that approximate engagement is made with the fingers or

grippers 51, 52 and 53. He does not necessarily have to make engagement with the fingers 51, 52 and 53, as such engagement is taken care of by the jogging movement of the fingers 45, 49 and 50. Automatic, positive and uniform register is in this manner obtained and the speed and output can be materially increased as the effort and work of the operator is merely directed to inserting the stock.

Another important feature is the fact that the fingers 51, 52 and 53 are raised when a previously printed card is released for ejection, thus presenting high projections which are easily engaged when the cards are inserted. In fact even a curled card can be easily handled as it will not have the same tendency to slide over the fingers as where a low registering finger is employed. The fingers 45, 49 and 50 are of course retracted below the table surface during the releasing and ejecting operation as it would otherwise be difficult to feed in the stock and similarly eject the same.

In actual operation the stock to be printed is placed upon the surface of a table when the lifting frame assumes its elevated or tilted position; a registry between the stock and the stencil screen being quickly and automatically obtained as the operator merely moves the stock into abutment with the finger 51. The fingers 49 and 50 insure engagement of the stock with the fingers 52 and 53, finger 45 simultaneously insures engagement with finger 51, and clamping of the stock takes place when the fingers are depressed or partially retracted. The lifting frame is next lowered and a reciprocal movement is imparted to the squeegee frame by means of the arms 28, while the lifting frame is in engagement with the table; the paint being first distributed over the screen or stencil, and secondly transferred therethrough by the pressure exerted through the medium of the squeegee. The squeegee frame comes to a temporary rest, the moment the return stroke has been completed and the lifting frame is then immediately raised. The fingers 45, 49 and 50 are then jogged back and retracted below the table surface; the fingers 51, 52 and 53 are simultaneously raised and the knock-out fingers are then released and will, due to the tension of the spring 40, move forward with a trigger-like movement, thus striking the stock now released with relation to the registering fingers with such force that it will be automatically ejected. The operator has during this period, grasped the next section of stock to be inserted and is therefore ready to move it into approximate register with the fingers 51, 52 and 53, the moment ejection has taken place. This cycle of operation is repeated and repeated and fairly unskilled

labor or operators may be employed as, practically speaking, the only duty required is that of feeding the stock.

If for any reason it happens that the operator may want to leave the lifting frame in raised position and secure the squeegee frame against reciprocal movement with relation thereto when assuming its rearmost position, it is accomplished by rocking a lever 90. This lever is pivotally mounted on the main frame A as indicated at 91. One end of the lever or that indicated at 92 is adapted to engage a notch 28^a formed in the arms 28, thus securing the arms 28, the rocker shaft 6 and the crank arm 27 against forward movement as long as engagement is maintained between the projection 92 and the arms 28. The rocker arm 21 is similarly locked against rocking movement by sliding bar 93. This sliding bar is connected with the member 92 by means of a link 94. This link exerts a pull on the bar 93 and moves it to a position where it will engage the rear side of the rocker arm 21, thus securing it against return movement when the lifting frame has been tilted. The remainder of the mechanism will of course operate, but as the lifting frame and the squeegee remain stationary, it is of no consequence whether the grippers, etc., are operated or not.

The operator may want to temporarily stop the main operating parts, for instance when more stock is required or when making temporary adjustments or otherwise, and it is obviously an advantage to be able to temporarily stop the main parts of the machine from operating as the top of the table 2 might otherwise become smeared or flooded with paint.

From the foregoing description it can be seen that the entire operation of the mechanism is automatic, and that the operator has no other work to take care of than that of feeding the stock to the machine. The output should therefore be great and in actual practice will approximate fifty impressions or transfers a minute. The speed may however be slightly varied as the skill of the feeder or operator increases. The quality of the work produced is materially improved; the work is uniform in appearance and the amount of paint or color employed is materially decreased; spoils are practically eliminated; smeared or dirty work is, practically speaking, inexcusable, and the wear and tear of the screen or silk fabric employed is materially lessened as uniform pressure is always applied thereto.

While certain features of the present invention are more or less specifically illustrated, I wish it understood that various changes in form and proportion may be resorted to within the scope of the appended claims, similarly that the materials and finish of the several parts employed may be

such as the experience and judgment of the manufacturer may dictate or varying uses may demand.

Having thus described my invention, what I claim and desire to secure by Letters Patent is—

1. In a machine of the character described a table, a stencil, a frame supporting the stencil; color applying and transferring means consisting of a receptacle and cooperating with the stencil and having spaced, spreading and pressure applying means, means for raising and lowering the stencil and frame, and means operating in timed sequence with the said means for transmitting a reciprocal movement to the color applying and transferring means with relation to the stencil.

2. In a machine of the character described a table, a stencil, color applying and transferring means cooperating with the stencil having spaced, spreading and pressure applying means, means operating in timed sequence with the said means for raising and lowering the stencil at regular timed intervals, and means operating in timed sequence with the said means for transmitting a reciprocal movement to the color applying and transferring means when the stencil assumes its lowered position.

3. In a machine of the character described a main frame, a table supported thereby, a stencil supporting frame hingedly attached to the table, depressible registering fingers mounted in the table, a cam shaft journaled in the main frame, means for driving the same, and means actuated by the cam shaft for intermittently raising and lowering the stencil frame about its hinges and for actuating the registering fingers.

4. In a machine of the character described the combination with the stencil supporting frame and the table with which it cooperates, of a squeegee supported by the stencil frame and reciprocal thereon, power actuated means for intermittently raising the stencil frame with relation to the table, other power actuated means for intermittently imparting a reciprocal movement to the squeegee, color applying and transferring means slidable over the stencil supporting frame with the squeegee.

5. In a machine of the character described the combination with the stencil supporting frame and the table with which it cooperates, of a squeegee supported by the stencil frame and reciprocal thereon, power actuated means for intermittently raising the stencil frame with relation to the table, other power actuated means for intermittently imparting a reciprocal movement to the squeegee, registering fingers projecting through the table and cooperating with the frame, ejecting means projecting through the table, and power actuated means for intermittent-

ly operating the ejecting means and for raising and lowering the registering fingers.

6. In a machine of the character described a main frame, a table supported thereby, a stencil frame supported by the table, color applying and transferring means supported by the stencil frame, registering fingers cooperating with the stencil frame and supported by the table, an ejecting mechanism supported by the table, a continuously rotating shaft journaled in the main frame, and means on said shaft for transmitting a reciprocal movement to the color applying and transferring means and for raising and lowering the stencil frame with relation to the table, said shaft also adapted to actuate means for raising and lowering the registering fingers with relation to the surface of the table, and to intermittently operate the ejecting mechanism.

7. In a machine of the character described a main frame, a table thereon, a stencil frame supported by the table and adapted to be raised and lowered with relation thereto, a pair of track members on the stencil frame, a color applying and transferring mechanism slidably mounted between said track members, a continuously rotated shaft journaled in the main frame, means actuated by said shaft for raising and lowering the stencil frame at timed intervals, a pair of arms one on each side of the main frame, a pivotal support for the lower ends of said arms, a connection between the upper ends of the arms and the color applying and transferring means for sliding the same over the stencil, and means on said shaft for transmitting an oscillating movement to the arms.

8. In a machine of the character described the combination with the color transferring stencil, of a squeegee reciprocally movable over the surface of the stencil, means cooperating with the squeegee and slidable over the stencil for delivering a coloring medium to the surface of the stencil, and means for applying pressure to the squeegee.

9. In a machine of the character described the combination with the color transferring stencil, of a squeegee reciprocally movable over the surface of the stencil, a receptacle for the reception of the coloring medium slidable over the stencil in unison with the squeegee and adapted to spread the color over the surface of the stencil, and means for applying pressure to the squeegee.

10. In a machine of the character described the combination with the color transferring stencil, of a squeegee reciprocally movable over the surface of the stencil, a color supplying and applying device supported by the squeegee and slidable over the stencil in unison therewith, and means for applying pressure to the squeegee.

11. In a machine of the character de-

scribed the combination with the color transferring stencil, of a squeegee reciprocally movable over the surface of the stencil, a color supplying and applying receptacle supported by the squeegee and slidable over the stencil in unison therewith, said receptacle having an opening formed in its bottom and extending from end to end of the receptacle, said opening being closed by contact of

5 the receptacle with the stencil surface, and means for applying pressure to the squeegee.

12. The combination with the stencil supporting frame, of a pair of track members secured one on each side thereof, a pair of rollers engaging each track member, a pair of head members supporting the rollers and interspaced with relation to each other, a squeegee vertically disposed between the head members, means for clamping the 15 squeegee, and means for raising and lowering the squeegee.

13. The combination with the stencil supporting frame, of a pair of track members secured one on each side thereof, a pair of rollers engaging each track member, a pair of head members supporting the rollers and interspaced with relation to each other, a pair of interspaced clamping plates disposed between the heads, a squeegee mounted 20 between said plates and adapted to be supported and secured thereby, and other means for raising and lowering the squeegee between the clamping plates.

14. The combination with the stencil supporting frame, of a pair of track members secured one on each side thereof, a pair of rollers engaging each track member, a pair of head members carrying the rollers and interspaced with relation to each other, a 25 pair of interspaced clamping plates disposed between the heads, a squeegee mounted be-

tween said plates and adapted to be supported and secured thereby, other means for raising and lowering the squeegee between the clamping plates, and a coloring supplying receptacle supported by the cross arms, said receptacle having a slot formed in its bottom portion extending from end to end of the receptacle, said opening being closed only by contact with the screen.

45 50

15. In a machine of the character described the combination with the stencil supporting frame and the table with which it cooperates, of a squeegee supported by the stencil frame and reciprocal thereon, power actuated means for intermittently raising the stencil frame with relation to the table, other power actuated means for intermittently imparting a reciprocal movement to the squeegee, registering fingers projecting through the table and cooperating with the frame, means for imparting a jogging movement to certain of the fingers, and means for imparting a gripping movement to all of the fingers, ejecting means projecting through the table, and power actuated means for intermittently operating the ejecting means for raising and lowering the registering fingers.
